CLAIM

We claim the ornamental design for a mud flap, as shown and described.

DESCRIPTION

FIG. 1 is a top, rear, and right side perspective view of a mud flap showing our new design as installed on a motor vehicle; FIG. 2 is a top, rear, and right side perspective view of the mud flap;

FIG. 3 is a rear elevation view thereof;

FIG. 4 is a front elevation view thereof;

FIG. 5 is a top plan view thereof;

FIG. 6 is a bottom plan view thereof;

FIG. 7 is a left side elevation view thereof; and,

FIG. 8 is a right side elevation view thereof.

The broken line showing of a motor vehicle and fastening brackets are provided for the purpose of illustrating environmental structures and form no part of the claimed design.
